UNITED STATES PATENT OFFICE

97,318

DESIGN FOR SHEET GLASS

Marc A. M. J. Galliano, Paris, France

Application March 21, 1935, Serial No. 55,996

Term of patent 14 years

To all whom it may concern:

Be it known that I, Marc A. M. J. Galliano, a citizen of France, residing at Paris, Republic of France, have invented a new, original, and ornamental Design for Sheet Glass, of which the following is a specification, reference being had to the accompanying drawing, forming part thereof.

In the drawing:

Figure 1 is a plan view of a piece of glass showing my design;

Figure 2 is a plan view of the reverse side of the same; and

Figure 3 is a transverse section taken on the line 3—3 of Figure 1.

The invention embodies a piece of sheet glass fabricated to provide a plurality of plane faced mirrors submerged below the plane surface of a transparent medium, with their mirror surfaces perpendicular to each other, with their intersecting edges forming regular hexagons in plan submerged below said surface; and forming as a whole, a series of interlocking tre-foils.

I claim:

The ornamental design for sheet glass as shown and described.

MARC A. M. J. GALLIANO.
